CLAIM

We claim the ornamental design for a port replicator, as shown and described.

DESCRIPTION

FIG. 1 is a front perspective view of a port replicator of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a cross-sectional view taken along the line 8-8 in FIG. 2; and,

FIG. 9 is an enlarged cross-sectional view of the area marked as 9 in FIG. 5 thereof.

The broken lines in the drawings depict portions of the port replicator that form no part of the claimed design.
